UNITED STATES PATENT OFFICE.

MEYER L. ROBBINS, OF NEW YORK, N. Y.

HINGE.

No. 902,606.

Specification of Letters Patent.

Patented Nov. 3, 1908.

Application filed March 31, 1908. Serial No. 494,418.

To all whom it may concern:

Be it known that I, MEYER L. ROBBINS, a citizen of the United States, and a resident of New York, borough of Manhattan, in the county of New York and State of New York, have made and invented certain new and useful Improvements in Hinges, of which the following is a specification.

My invention relates to an improvement in rings, lockets, brooches, and in fact, to any article of jewelry formed with a receptacle having a hinged lid or cover therefor, the object of the invention being to provide a hinge for said cover which shall be neat in appearance, (in fact, practically invisible), which shall be strong and durable, and which shall be comparatively simple and inexpensive to construct and assemble.

With these and other ends in view, the invention consists in certain novel features of construction and combinations of parts, as will be hereinafter fully described and pointed out in the claims.

While the invention is applicable to many articles of jewelry, for the sake of illustration I have shown it as applied to a ring, Figures 1 and 2 showing the lid or cover, the sectional pindle and the ring detached or separated. Fig. 3 is a plan view showing the parts assembled, but prior to the completion of the hinge. Fig. 4 is a sectional view taken through the hinge on the line 4-4 of Fig. 5. Fig. 5 is a sectional view taken on the line 5-5 of Fig. 4. Fig. 6 is a plan view of the finished article.

Referring to the drawings, A represents a common type of ring provided with the well or receptacle B surrounded by the outwardly extending flange C, over which latter snaps or fits the cover or lid D.

As heretofore constructed, hinges for connecting the lid or cover to the body of the article, have been made up of two or three loops or sleeves secured respectively to the lid or cover and to the article to which the latter is attached, a pindle consisting of a bar or wire extending through the several sleeves formed on or secured to the several parts. In those instances where the lid or cover is small or contracted in dimensions, the sleeves or loops must be made correspondingly small, necessitating fine and delicate work, and at best providing a hinge which is necessarily weak and in many instances unable to withstand the strain imposed upon it.

In my improved hinge, I employ but one loop or sleeve E, made integral with the lid or cover, or if desired, soldered or otherwise secured thereto, and as but this one sleeve or loop is necessary to the proper construction of the hinge, it may be made comparatively long, thereby providing a safe and strong bearing, the length of the sleeve being nearly equal to the width of the lid or cover. Into the opposite ends of this sleeve E fit the ends of a sectional pindle F, each section having its inner end reduced in diameter, forming the shoulders H, these shoulders abutting against the ends of the sleeve when the parts are assembled, as clearly illustrated in Fig. 4, and as the outer surfaces of the larger ends of the sections F lie flush with the outer surfaces of the sleeve E, the assembled parts in the finished article have the appearance of being made in one piece.

In constructing the hinge, it has been my practice to make the sections F of such length that they may be easily and conveniently handled by the workmen, the outer ends projecting somewhat beyond the lid D, as illustrated in Fig. 3, these ends being subsequently cut off as hereinafter described. In the body of the ring, and in proximity to the receptacle B, is cut or otherwise formed the groove or recess I, curved to conform to the curvature of the sleeve E and sectional pindle F, and in size to nicely contain the same.

In assembling and securing the parts together, the reduced ends of the pindle sections F are inserted in the opposite ends of the sleeve E until the shoulders H formed on the sections, abut against the ends of said sleeve. The lid D is then snapped over the flange C, the said sleeve and pindle nicely fitting within the recess I and completely filling the same, as illustrated in Fig. 3. The larger ends of the pindle sections F are then soldered into the groove or recess E, in order to permanently and securely hold the same in place. The extending or projecting ends of these sections are then cut off to their proper length, in order to conform and harmonize with the appearance of the body of the article and lid.

It will be understood from the foregoing that by means of this construction, the lid may be turned or swung on the reduced ends of the pindle sections, the hinge itself being safe, strong and durable, capable of with-

standing the strain that is usually imposed upon the same, and practically invisible, as the sleeve D and pintle sections completely fill the groove or recess I, and have the appearance of being made integral with the ring or body of the article to which the hinge is applied.

Having fully described my invention, what I claim as new and desire to secure by Letters Patent, is:—

1. The combination with a lid provided with a sleeve, of a body, and a sectional pintle, the adjacent ends of which are fitted in the opposite ends of said sleeve and having their outer ends secured to said body, substantially as described.

2. The combination with a lid provided with a sleeve, of a body provided with a groove into which said sleeve fits, and a sectional pintle, the adjacent ends of which are fitted in the opposite ends of said sleeve and their outer ends secured in said groove, substantially as described.

3. The combination with a lid provided

with a sleeve, of a body, and a sectional pintle, the adjacent ends of said pintle being reduced in diameter and fitted in the opposite ends of said sleeve, and having their larger outer ends secured to said body, substantially as described.

4. The combination with a lid provided with a sleeve, of a body provided with a groove into which said sleeve fits, and a sectional pintle, the adjacent ends of the sections of said pintle being reduced in diameter and fitted in the opposite ends of said sleeve, the larger outer ends of said pintle being secured in the groove in said body, substantially as described.

Signed at New York, borough of Manhattan, in the county of New York and State of New York, this 27th day of March, A. D. 1903.

MEYER L. ROBBINS.
